Primary Examiner — Maria J. Edwards*Assistant Examiner* — Dina Michelle Hoeynck(74) *Attorney, Agent, or Firm* — Getz Balich LLC(57) **CLAIM**

I claim the ornamental design for a camera head, as shown and described.

DESCRIPTION

FIG. 1 is a front perspective view of the camera head;
FIG. 2 is a back perspective view of the camera head;
FIG. 3 is a front plan view of the camera head;
FIG. 4 is a back plan view of the camera head;
FIG. 5 is a top plan view of the camera head;
FIG. 6 is a bottom plan view of the camera head;
FIG. 7 is a right-side plan view of the camera head; and,
FIG. 8 is a left-side plan view of the camera head.
The broken lines depict portions of the article that form no part of the claimed design.

1 Claim, 6 Drawing Sheets(56)
